UNITED STATES PATENT OFFICE

GEORGE F. THOMAS, OF BERWYN, AND OTTO J. HERB, OF CHICAGO, ILLINOIS, ASSIGNEES TO ALEMITE CORPORATION, OF CHICAGO, ILLINOIS, A CORPORATION OF DELAWARE

GRAVITY LUBRICATING SYSTEM

Application filed March 15, 1928. Serial No. 261,779.

Our invention relates, generally, to lubricating apparatus and more particularly to a gravity system and apparatus for lubrication of a plurality of bearings from a single source in which means are provided for adjusting the flow to each individual bearing.

It is an object of our invention to provide an improved gravity lubricating system for a plurality of bearings in which the flow of lubricant to each of the bearings may be easily and conveniently adjusted.

A further object is to provide an improved adjustable sight feed resistance unit, in which a gauge is provided which at all times gives a readily observable indication of the rate of feed.

A further object is to provide an improved resistance unit, all characteristics of the operation of which are visible to the operator.

Other objects will appear from the following description, reference being had to the accompanying drawing, in which

Fig. 1 is a diagrammatical vertical sectional view of an illustrative gravity system, two of the resistance units being shown in elevation;

Fig. 2 is a central vertical section of a modified form of resistance unit; and

Fig. 3 is a similar view of a second modified form.

The source of lubricant in our improved system comprises a reservoir 4 having a base casting 6 and a cylindrical wall 8 secured to the casting. A removable cover 10 fits over the top of the cylindrical wall 8. A strainer 12, preferably of wire mesh, is secured at the lower end of the cylindrical portion of the reservoir 4 and rests upon a shoulder 14 formed in the casting 6. A gauge glass 16 is secured to the reservoir 4 in any suitable manner.

The base casting 6 slopes toward a central outlet port 18 which has a suitable seat 20 at its upper edge. A float 22 of cork or other

suitable material has a ball valve 24 secured thereto by a wire 26 which passes through the cork float 22 and is bent over the top thereof.

When the reservoir 4 is filled or partially filled with lubricant the float will rise upwardly until it comes in contact with the strainer screen 12, thus permitting lubricant to flow from the reservoir into the outlet passage 18. As the reservoir becomes empty the float will drop, permitting the ball 24 to rest against its seat 20, thereby preventing further flow of lubricant from the reservoir. It is desirable thus to cut off the flow from the reservoir to the conduit system when the lubricant is substantially exhausted from the reservoir so as to prevent the possibility of air being drawn into the conduit system. The presence of air in the conduit system is the cause of inaccurate distribution of the lubricant and occasional failure to operate properly.

The base casting 6 has a suitable bracket 28 by which the reservoir may be secured to a part of the machine to be lubricated. The outlet passage 18 may be closed by a manually operable valve 30, reciprocable in a bore 31. The stem 32 of the valve 30 is threaded in a bushing 34 which is screwed into the casting 6. Any suitable number of conduits 36 are secured to the base casting 6 by bushings 38 and communicate with the bore 31. These conduits may lead to an individual resistance unit or may be branched and one conduit supply several resistance units with lubricant.

Each of the resistance units or flow resistance fittings comprises a body 40 having an axial bore 42 at its lower end and being connected by a union 44 with one of the bearings 41, 43, 47 to be lubricated. A glass tube 46 is held between the end of the bore 42 and the end of the nipple 44, suitable gaskets 45 being provided to form lubricant-tight seals. If desired, a drip fitting 48, which consists of a cone-shaped disc having horizontal flanges

and an aperture at the tip of the conical portion may be provided. The lubricant flowing through the resistance unit will thus form drops at the lower end of this fitting. Suitable sight openings 50 are formed in the body 40 so that the rate of feed may readily be observed.

The conduit 36 from the reservoir is connected adjacent the upper ends of the body 40 by means of a bushing 52 and communicates with a threaded bore 54. A threaded plug 56 is partially screwed into the bore 54 and has a stem 58 projecting upwardly through the body 40. A gasket 60 prevents leakage of lubricant past the stem 58. The threads on the plug 56 are not full V but have their sharp edges ground off. A helical passage of very small cross sectional area is thus formed between the plug 56 and the groove between the threads in bore 54. The length of this passage may be varied by manually rotating the stem 58 and thereby screwing the plug 56 into or out of the bore 54. Variation in the length of this passage causes an approximately inverse proportional variation in the flow resistance of the fitting and in the rate of lubricant flow.

In operation the reservoir 4 is filled with lubricant which gradually feeds through the large strainer 12 through the outlet passage 18, since, due to the presence of lubricant, the float 22 will have raised the ball valve 24 from its seat 20. Upon opening the valve 30 lubricant will flow by gravity through the conduits 36 to the resistance units and hence to the bearings associated with the units. The flow to the bearing may readily be observed through the sight openings of the resistance units and by adjusting the resistance plugs 56 of the various units, the flow to each bearing may be fixed to suit the requirements of the bearing. Compensation may thus be made for the differences in the level of the different units and each fitting or unit adjusted so that its bearing will receive the desired quantity of lubricant irrespective of its position with respect to the reservoir 4. It is, of course, understood that the reservoir will be placed at a level sufficiently above the highest bearing of the system to provide an adequate hydrostatic head for gravitational flow.

In Fig. 2 is shown a modified form of resistance unit in which the rate of flow of lubricant to the bearing may be determined at a glance. The fitting comprises a substantially tubular body 64 which is attached to a bearing 66 by means of a union 68. This body 64 has suitable sight openings 70 and 72 and has glass tubes 74 and 76 secured between an internal shoulder 78, a member 80 and the nipple 68, respectively, suitable gaskets being provided to effect a lubricant-tight seal at the ends of the glass tubes. A fitting 80, which is threaded into the upper

end of the tubular body 64, is internally threaded to receive a resistance plug 82, a portion of the thread of which is ground off so as to provide a helical passageway between the plug and the fitting 80. The plug 82 has a kerf by which it may be screwed into the fitting 80 any desired distance, thus adjusting the length and hence the flow resistance of the helical passage between the plug and fitting. A conduit 36 leading from the source of lubricant supply may be attached to a member 84 in any well-known manner, such as by means of the compressing ring 86 and gland 88. The member 84 has an outlet passage 90 of small diameter which is normally covered by a thin disc valve 92. This disc is preferably made of Empire cloth or some other suitable light fabric material which is impervious to oil. The disc is confined, so that it may move only a short distance from the face at the edge of the outlet passage 90, by a cage 94 which is rigidly secured in the member 84 and has an upwardly projecting central point 96 upon which the valve 92 rests when in open position. This check valve construction is more fully disclosed in the co-pending application of Oscar U. Zerk, Serial No. 207,609, filed July 22, 1927, and for the present purposes may be considered as a check valve which will offer substantially no resistance to flow in one direction but will close quickly upon slight differences of pressure tending to produce flow in the opposite direction.

The shoulder 78, formed integrally with the tubular body 64, has a tapered threaded bore into which a screw 98 is threaded. The threads of this screw are preferably ground so that there will be a helical passage of very small cross sectional area between the screw 105 and the shoulder 78. The passage, however, may be greater in cross sectional area than the passage between the plug 82 and the fitting 80.

Thus, in operation of the device lubricant will flow by gravity through the conduit 36 past the check valve 90 and between the plug 82 and fitting 80 and will accumulate within the glass tube 74 but will pass outwardly therefrom through the helical passage between the screw 98 and the shoulder 78 and will collect at the pointed end of the screw 98 and flow therefrom in drops so that the rate of flow may be readily observable and measured by counting the number of drops. The lubricant will accumulate within the glass well 74 until a hydrostatic head is attained which is sufficient to cause flow past the plug 78 at the same rate that oil enters the glass 74 through the helical passage between the plug 82 and the threaded bore in member 80.

When this condition is obtained the level of oil in the tube 74 will remain constant and serve not only as an indication that the

oil is being fed to the bearing but will, by its height, indicate the rate at which the oil is flowing to the bearing. If, however, the oil fills up the tubes 74 and 72, the operator 5 will be apprised of the fact that the bearing is clogged and not taking the proper amount of oil. The height of the column of oil which is present in the tube 74 during normal operation is of course dependent upon the pres- 10 sure of the lubricant at the inlet of the fitting, the flow resistance around the plug 82 and the flow resistance around the plug 98. The two flow resistances may be adjusted so that, for any desired rate of flow, the oil in the 15 tube 74 will stand at a certain level.

In other respects the operation of the unit shown in Fig. 2 is substantially the same as that illustrated in Fig. 1. Of course, the fitting shown in Fig. 1 has the advantage that 20 its rate of flow can be adjusted without taking the unit apart, whereas that shown in Fig. 2 cannot be so readily adjusted.

In Fig. 3 we have shown a modified form 25 of resistance unit which has all the advantages of the type shown in Fig. 2 and the additional advantage of the type shown in Fig. 1, in that its resistance may be readily adjusted without taking the unit apart. Since in its details this unit is a composite of 30 the units shown in Figs. 1 and 2, similar reference characters have been used to designate similar parts. It is believed that from the previous description the construction and 35 method of operation of this unit will be apparent.

While we have shown and described particular embodiments of our invention, we do not wish to be limited to the details disclosed 40 therein but desire the scope of our invention to be limited only by the claims which follow.

1. In a central lubricating system, the combination of a source of lubricant, a plurality of bearings to be lubricated, conduits connecting said source with said bearings, and a lubricant flow controlling fitting interposed 45 between said conduits and each of said bearings, each of said fittings comprising a pair of flow resistance passages and a transparent well intermediate said passages.

2. In a gravity lubricating system of the class described, the combination of a lubricant reservoir, a plurality of bearings located at different levels and lower than said 55 reservoir, a flow metering fitting connected to each of said bearings, conduits connecting said fittings with said reservoir, means operable without disconnecting said conduits and fittings for regulating the flow of lubricant 60 to each of said bearings in accordance with its lubricant requirement and position relative to said reservoir, a transparent well in each of said fittings, an adjustable flow retarding element between said well and the 65 bearing associated with the fitting, and a

transparent conduit between said flow retarding element and said bearing.

3. In a central lubricating system, the combination of a source of lubricant, a plurality of bearings to be lubricated, conduits connecting said source with said bearings, flow resistance fittings in said conduits between said source and said bearings, said fittings comprising a minute channel for the flow of lubricant, means to adjust the effective length 70 of said channel, a transparent well adapted to receive the lubricant flowing through said channel, a flow retarding passageway leading from the bottom of said well, means to collect the lubricant which has flowed through 75 said passageway and to form it into readily visible drops, and transparent means through 80 which the drops of lubricant may be observed.

4. In a gravity lubricating system of the class described, the combination of a lubricant 85 reservoir, a plurality of bearings located at different levels and lower than said reservoir, a flow metering unit connected to each of said bearings, conduits connecting said fittings with said reservoir, means operable 90 without disconnecting said conduits and fittings for regulating the flow of lubricant to each of said bearings in accordance with its lubricant requirement, a transparent lubricant collecting well in each of said fittings 95 adapted to receive lubricant from said unit, and adjustable means including a restricted passageway for retarding the flow of lubricant from said well to the bearing, whereby 100 the lubricant will be stored in said well and its level serve as an indication of the rate of flow to the bearing.

5. A lubricant receiving fitting for use in centralized lubricating systems comprising a main restriction for the flow of lubricant, a 105 transparent well for receiving the lubricant from said restriction, a supplemental flow resistance receiving lubricant from the bottom of said well, a sight aperture beneath said flow resistance whereby the flow past 110 said flow resistance may be observed, and means for conducting lubricant from said flow resistance to a bearing to be lubricated.

6. A lubricant metering fitting comprising an inlet, means adjacent the inlet for restricting the flow of lubricant, a well for receiving the lubricant which has flowed through said restriction, an internally threaded opening at the bottom of said well, a plug having mutilated threads screwed in 115 said opening, said plug having means for collecting the lubricant which has flowed between it and said opening into drops, a sight glass around said means on said plug whereby the drops therefrom may be observed, and means for conducting the lubricant dripping from said means on said plug to a bearing to be lubricated.

7. In a central lubricating system, the combination of a source of lubricant, a fitting 120

adjacent each of said bearings, a branch conduit system connecting said source with said fittings, metering means in each of said fittings, a lubricant reservoir in each of said fittings, and adjustable means between each of said reservoirs and each of said bearings whereby the lubricant level in said reservoirs may be varied.

In witness whereof, we hereunto subscribe
10 our names this 5 day of March, 1928.

GEORGE F. THOMAS.
OTTO J. HERB.
